[57] CLAIM

The ornamental design for a combined cosmetic bottle and cap, as shown and described.

DESCRIPTION

FIG. 1 is a front elevational view of our combined cosmetic bottle and cap;

FIG. 2 is a rear elevational view thereof; the left and right views being identical;

FIG. 3 is a top plan view thereof;

FIG. 4 is a bottom plan view thereof;

FIG. 5 is a view similar to that of FIG. 1, but with the cap removed;

FIG. 6 is a cross-sectional view taken along the line 6—6 of FIG. 1; and,

FIG. 7 is a top plan view of the cosmetic bottle shown in FIG. 5.

The cosmetic bottle is shown without the cap in FIGS. 5 and 7 for clarity of illustration.
